ROTARY PACKER HEAD

Harold G. Holston, Caruthers, Calif.

Application February 9, 1953, Serial No. 335,639

7 Claims. (Cl. 25—36)

This invention relates generally to apparatus for making concrete pipe.

The invention is directed particularly to, and it is a major object to provide, an improved rotary packer head for forming and internally finishing concrete pipe in an upstanding, cylindrical jacket or form.

Another important object of the invention is to provide a rotary packer head which includes a troweling cylinder secured axially on the lower end of a driven, vertically reciprocable spindle, and a novel assembly of loose-wall forming and thickness control blades, and following troweling and compacting rollers, mounted in circumferentially and substantially equi-distantly space relation on a top plate included in the cylinder and to which top plate said spindle is secured.

A further object of the invention is to provide a rotary packer head, as above, which embodies a novel arrangement for removably securing the top plate in the troweling cylinder.

An additional object of the invention is to provide a rotary packer head which works fast and cleanly to form concrete pipe with a uniform density or pack of the mix and an excellent internal finish.

A further object of the invention is to provide a rotary packer head which is operative to produce concrete pipe of relatively small diameter, yet maintaining desirable physical characteristics, such as the aforesaid uniform density and excellent internal finish.

A still further object of the invention is to provide a rotary packer head which is operative to produce such pipe with a single pass of the packer head through the cylindrical jacket or form.

It is also an object of the invention to provide a rotary packer head which is designed for ease and economy of manufacture and operation; the device being simple but rugged, and capable of long usage, with a minimum of repair or replacement of parts.

Still another object of the invention is to provide a rotary packer head which is practical and reliable, and yet exceedingly effective for the purpose for which it is designed.

These objects are accomplished by means of such structure and relative arrangement of parts as will fully appear by a perusal of the following specification and claims.

In the drawings:

Fig. 1 is an elevation of the rotary packer head as in use.

Fig. 2 is a plan view of the rotary packer head, with the spindle in section.

Fig. 3 is a transverse sectional elevation on line 3—3 of Fig. 2.

Referring now more particularly to the characters of reference on the drawings, the numeral 1 includes a vertical-axis troweling cylinder whose outside diameter is substantially the inside diameter of the concrete pipe 2 which is produced in a cylindrical jacket or form 3.

The troweling cylinder 1 is of substantial height, and its lower edge is chamfered, as at 4.

A circular top plate 5 engages in matching relation in the upper end of the troweling cylinder 1, such top plate 5 being supported, and secured in position, as follows:

The top plate 5 is bevel cut circumferentially at its lower corner, as at 6, and such bevel cut portion rests at circumferentially spaced points in matching relation on lugs 7 which project radially inwardly from the cylinder 1; the upper faces of such lugs being inclined downwardly and inwardly in order to provide such matching engagement.

A circular bottom clamping plate 8 is disposed in the cylinder 1 beneath the lugs 7, abutting against the horizontal bottoms thereof; the clamping plate 8 being secured to the top plate 5 in hold-down relation to the latter by studs 9 having nuts 10 threaded thereon.

For ease of assembly and disassembly, the bottom plate 20 8 is formed with cutouts or peripheral notches 11 normally circumferentially offset from the lugs 7. However, upon loosening of the nuts 10 and bottom plate 8 the latter may be turned sufficiently to permit said lugs to register with the notches 11, whereby the assembly of bottom plate 8 and top plate 5 may be drawn upwardly out of the cylinder 1.

A vertical spindle 12 is fixed at its lower end, as at 13, centrally to the top plate 5; such spindle 12 being of substantial height and provided at its upper end with a connection 14 adapted to attach to the rotary, vertically reciprocable drive shaft (not shown) of a rotary packer head type, concrete pipe making machine.

On opposite sides of the spindle 12, the top plate 5 is fitted with a pair of vertical axis rollers 15 of substantial diameter; such rollers having their outermost face disposed to work in substantially the same vertical plane as the adjacent side of the troweling cylinder 1. The rollers 14 include internal bearings (not shown), and a spindle 16 projects downward from each roller 15 through the top plate 5, being secured to the latter by a threaded-on nut 17. The bottom plate 8 is cut away, as at 18, to provide access to the nuts 17.

Being opposed, the rollers 15 lie 180° apart, and intermediate such rollers—i. e. 90° from each thereof, and on opposite sides of the spindle 12—the device is fitted with upstanding, radially projecting mounting brackets 19. The mounting brackets 19 are for the purpose of supporting upstanding, loose-wall forming and thickness control blades 20 which are circumferentially arcuate on their outer faces; such faces being concentric to the axis of rotation of the packer head. The blades 20 each include, and trail from the outer edge of, an inwardly extending upstanding attachment and mix distributor plate 21 secured to the mounting brackets 19 in overlapping and radially adjustable relation thereto by cross bolts 22, each of which extends through a radially elongated slot 23 in the corresponding mounting bracket. The brackets 19 project from an unbroken top-to-bottom connection with the adjacent portion of the spindle 12, so that the brackets, together with said spindle portion, and the plates 21, form a continuous transverse wall between the opposed blades 20.

The plates 21 are set so that the outer faces of the control blades 20 run in a predetermined circumferential path which lies inwardly of the circumferential path of the outer faces of the rollers 15; this for the reason hereinafter described.

When the above described rotary packer head is in use, it is simultaneously rotated at substantial speed and moved upwardly in the jacket 3. At the same time a controlled quantity of concrete mix is fed into the jacket 3 from its upper end by means not here shown; such mix

falling directly onto the circular top plate 5, and then being distributed centrifugally outward in a horizontal direction by the mix distributor plates 21.

From the outer ends of the mix distributor plates 21, the mix discharges forcefully against the cylindrical jacket 3, whence the trailing blades 20 initially shape the pipe in loose-wall form; the mix being controlled as to proper initial or loose wall thickness by said blades 20. As the outer faces of such blades 20 are concentric to the axis of rotation, and run inwardly of the path of the outer faces of rollers 15 and cylinder 1, the function of said faces of blades 20 is one of pipe wall formation rather than compaction.

As the blades 20 control the initial thickness of the loose wall, overloading of the following rollers 15, and which function to forcefully compact the pipe wall, is effectively prevented.

Thus, by reason of the fact that the blades 20 accurately determine the amount of mix therein and form the loose wall ahead of the rollers 15, the load on the latter is maintained within reasonable limits, and such rollers can function to effectively compact said loose wall to final density and thickness.

With the above parts of the packer head operative as described, the density is very even throughout, and an improved wall formation is attained.

With upward and rotary travel of the packer head, the concrete pipe 2, as initially formed by the blades 20, and compacted by rollers 15, is further worked by the depending troweling cylinder 1; this to assure that the formed pipe, while wet, cannot collapse under the working pressures exerted by said blades and rollers.

The herein described rotary packer head produces pipe 2 which has a very excellent internal finish; the finish being even, relatively smooth, and with a minimum of imperfection.

By virtue of the particular construction of the described rotary packer head, including the relationship of the blades 20 and rollers 15 on the top plate 5, the device is capable of use to manufacture concrete pipe of relatively small size, even down to 8" pipe.

As shown, the blades 20 and plates 21 are of substantially greater height than the rollers 15; the advantage being that excess mix, carried ahead of said blades and plates, cannot spill rearwardly into the path of said rollers to overload the same and cause variance in the final wall structure of the pipe.

The purpose of the radial adjustment of the plates 21 is to regulate the desired thickness of the initially formed loose wall, and also to compensate for fine or coarse mix.

By reason of the substantial equi-distant circumferential spacing of the blades 20 and rollers 15 the rotary packer head is nicely balanced and runs without vibration, which further assures of the manufacture of pipe having constant wall thickness.

From the foregoing description it will be readily seen that there has been produced such a device as substantially fulfills the objects of the invention, as set forth herein.

The present application is a continuation of application, Serial No. 173,989, filed July 15, 1950, and now abandoned.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A rotary packer head, for a concrete pipe making machine, comprising a vertical axis troweling cylinder, a circular top plate in the upper end of the cylinder, means releasably securing the top plate in place in the cylinder, a spindle upstanding centrally from the top plate, and pipe forming and working instrumentalities mounted on the top plate about said spindle; said top plate securing means including inward projections on the cylinder, the top plate seating on the projections, a bottom plate abutting the projections from above, and releasable tie elements connecting said plates and clamping the same against said projections.

2. A rotary packer head, as in claim 1, in which said projections have downwardly and inwardly inclined upper faces, and the lower circumferential corner of the top plate being bevel cut to match.

3. A rotary packer head, as in claim 2, in which the projections are radially inwardly extending lugs; the bottom plate having lug escape notches in the periphery thereof normally circumferentially offset from said lugs.

4. A rotary packer head, for a concrete pipe making machine, comprising a vertical axis troweling cylinder, a solid surfaced top plate secured in the upper end of the troweling cylinder adapted to receive concrete mix thereon from above, a driven vertical spindle extending from the top plate centrally thereof, opposed vertical-axis troweling and compacting rollers mounted in a fixed position on the top plate with the outer faces of the rollers running in substantially the vertical plane of the outer face of the cylinder, upstanding mix distributor plates rigid with and projecting upwardly from the top plate between the rollers, and opposed loose-wall forming and thickness control blades projecting from the radially outer edge of the plates, said blades having convexly arcuate outer faces disposed adjacent but radially inward of said vertical plane of the cylinder face.

5. A head, as in claim 4, with means mounting the distributor plates in connection with the top plate and comprising opposed upstanding brackets secured to the top plate and extending radially of the axis of the spindle in lapping engagement with said distributor plates on the following side thereof, and means removably securing the engaged brackets and plates together.

6. A head, as in claim 4, in which the blades are disposed substantially equidistant between the rollers.

7. A head, as in claim 4, in which said blades and the corresponding distributor plates extend upwardly from the top plate to an upper edge termination in a common horizontal plane a substantial distance above the upper ends of the rollers.
